UNITED STATES PATENT OFFICE

JOHN DEUTSCH, OF NEW YORK, N. Y., ASSIGNOR TO THE ALLEN-SHERMAN-HOFF COMPANY, A CORPORATION OF PENNSYLVANIA

DISPOSAL OF FURNACE RESIDUES

Application filed June 5, 1929. Serial No. 368,716.

This invention relates to the handling of solids, more particularly ash from power plant furnaces.

Heretofore ash has been handled by being dropped into a hopper and then at intervals removed from the hopper onto an inclined wall from which small amounts of the ash was washed into a sluiceway. Originally this apparatus required considerable vertical space or "head room" in the boiler house. 10 Various improvements have resulted in decreasing the head room required and at the same time increasing somewhat the width or length of the hopper.

By my present invention I have provided an apparatus by which substantially all head room between the hopper and sluiceway has been eliminated and by which hoppers of greatly increased width and practically any length can be used. The practical result of the invention is that hoppers can be constructed with the same capacity as, but much less height than hoppers heretofore used. This results in further savings in boiler house construction costs and correspondingly measures the value of this invention.

In the drawings accompanying and forming a part of this specification

Fig. 1 is a longitudinal vertical sectional view of one form of apparatus embodying my invention; and

Fig. 2 is a top plan view partly in section showing my invention embodied in a different type of ash hopper; and

Fig. 3 is a transverse sectional view taken on line 3-3 of Fig. 1; and

Fig. 4 is a longitudinal sectional view taken substantially on line 4-4 of Fig. 2.

In Figs. 1 and 3 the hopper is formed by lateral walls 1 which extend upwardly from the basement floor 2 of a boiler house, and bottom walls 3 which are inclined from the middle of the hopper toward either end. The lower ends of walls 3 project through lateral walls 1 where openings 4 are provided and terminate just above screens or grids 5 located in the top of a sluiceway 6. The grid is substantially flush with the top of the basement floor 2. Enough slope is given walls 3

to insure ready flow of water and ash over it to the sluiceway 6.

A pivoted door 7 counterweighted as at 8 serves to close and seal each opening 4 and to retain ash and gas under pressure in the 55 hopper. A housing 9 is built around each grid 5 and door 7 as shown to permit ash to pass through the doorway and into sluiceway 6 without escape of dust into the basement or entry of air into the hopper from 60 the basement. Each housing 9 has a door 10 for inspection and clean out purposes.

Inside each housing 9, a high pressure pipe line 11 is provided. This line has a nozzle 12 disposed to discharge water under pressure against ash on wall 3 substantially parallel to the top surface of and close to the wall 3. By means of a ball and socket joint in the line 11 the line can be moved back and forth so as to discharge water from nozzle 12 across 70 the full width of wall 3 and opening 4.

Ash washed through grids 5 is received on a fluid conveyor formed by water discharged through nozzles 13 in a sluiceway 6 and is thereby carried away.

Either nozzle 12 may be actuated independently of the other or both may be actuated together. When both are operated at once care should be taken, with an arrangement as shown in Fig. 1, that the sluiceway capacity be not exceeded due to the rapid discharge of ash thereinto.

At the apex of the bottom walls 3 a T-shaped member 14 is positioned, the prime purpose of this device being to intercept 85 water from nozzle 12 and return it to walls 3. Otherwise when much of the ash has been removed from a wall 3 the water might overshoot the apex and so wet the ash on the other side as to interfere with the regular 80 discharge of the ash on that side. Also it is an advantage to return the water to the wall 3 so it will wash more ash into the sluiceway.

In Figs. 2 and 4 I have shown how my invention may be utilized with a hopper of 95 considerable width as well as length but without any head room between the hopper and floor being required and without any loss in speed of ash removal from the hopper.

In these figures the hopper 15 is substan-

100

tially like the hopper of Fig. 1 but has a width corresponding to the length of the hopper of Fig. 1 and a length several times the length of the latter hopper. There a plurality of openings 4 and doors 7 on each side of the hopper 15 and sluiceways 16 extend along each side of the hopper. These sluiceways 16 are similar to sluiceway 6 of Fig. 1 but run at right angles to the direction of sluiceway 6 in Fig. 1.

- 10 By the arrangement of parts of Figs. 2 and 4 ash or solids can be removed from the hopper simultaneously on both sides without danger of clogging either sluiceway. Ample hopper capacity is thus provided with less vertical height than has been possible heretofore.

An important advantage incident to this invention is that a considerable positive gas pressure may be maintained in the hoppers when the doors 7 are closed. This is desirable when such pressure is required to force air up through grinders above or in the upper part of the hopper to complete the combustion of partly burned fuel thereon and thus to increase the furnace or stoker efficiency. The hopper and its doors 7 effectually prevent escape of gas under pressure in the hopper independently of any gas or air pressure in the sluiceway or outside of the doors, the weight of the doors resting against the hopper wall about the openings 4 and the counterweights 8 effectually sealing openings 4 against gas escape therethrough.

35 Having thus described my invention in detail for purposes of explanation I wish to be understood as defining the scope of my invention, not by such description, but by what is claimed.

What is claimed is:

- 40 1. Apparatus for handling loose solids comprising a hopper formed by lateral walls extending upwardly from adjacent to a floor, there being a plurality of openings provided in the opposite lateral walls near the floor, bottom walls for the hopper extending downwardly from intermediate the opposite lateral side walls and projecting through said openings, doors for closing the openings, means for directing a stream of liquid under pressure through said openings and substantially parallel to the top of said bottom walls, and sluiceway means below the said floor for receiving and carrying away solids washed from the bottom walls by said fluid.

2. Apparatus for handling loose solids comprising a substantially horizontal floor, a hopper formed by lateral walls extending upwardly from adjacent to said floor, there being a plurality of openings provided in the opposite lateral walls near the floor, bottom walls for the hopper extending downwardly from a point intermediate the opposite lateral side walls and projecting

through said openings, doors for closing the openings, means for directing a stream of liquid under pressure through said openings and substantially parallel to the top of said bottom walls, and a sluiceway along each of two opposite sides of the hopper and beneath the projecting portions of the bottom walls each adapted to receive and carry away solids discharged from the hopper through the plurality of openings on one side of the hopper.

3. Apparatus for handling loose solids, comprising a hopper having upwardly extending side walls, a discharge opening in the bottom part of one of said side walls, a bottom wall for said hopper sloping downwardly to said discharge opening and having a portion projecting therethrough, a door for closing said opening, means for directing a stream of liquid under pressure through said opening into said hopper and substantially parallel to said bottom wall, and a sluiceway disposed beneath the projecting portion of said bottom wall and adapted to receive and carry away solids discharged from the hopper through said discharge opening.

4. Apparatus for handling loose solids comprising a hopper having upwardly extending lateral walls and a discharge opening in the lower part of one of said walls, a bottom wall for said hopper sloping downwardly toward said discharge opening and having a portion projecting through said opening, a door for closing the said opening, a movable nozzle disposed outside of said hopper and adapted to direct a stream of liquid under pressure through said opening, and a sluiceway disposed below said opening and adapted to receive and carry away solids removed from said bottom wall by fluid under pressure from said nozzle.

5. Apparatus for handling loose solids comprising a hopper having upwardly extending side walls, one of said side walls having a discharge opening in its lower portion, a slanting bottom wall having its lower end at said discharge opening and having a portion extending through said discharge opening, means for closing said discharge opening, a housing lying outside of said hopper walls and adapted to enclose said discharge opening, and means within said housing for directing a stream of fluid under pressure through said opening into said hopper.

6. Apparatus for handling loose solids comprising a hopper having upwardly extending side walls, one of said side walls having a discharge opening in its lower portion, a slanting bottom wall having its lower end at said discharge opening and having a portion extending through said discharge opening, means for closing said discharge opening, a housing lying outside of said hopper walls and adapted to enclose said discharge

opening, and a nozzle movably supported within said housing and adapted to direct a stream of fluid under pressure through said discharge opening against the material within said hopper.

- 5 7. Apparatus for handling loose solids comprising a hopper having upwardly extending side walls, one of said side walls having a discharge opening in its lower portion, a slanting bottom wall having its lower end adjacent said discharge opening and having a portion extending through said discharge opening, means for closing said discharge opening, a housing lying outside of said hopper walls and adapted to enclose said discharge opening, a nozzle movably supported within said housing and adapted to direct a stream of fluid under pressure through said discharge opening against the material within said hopper, and a sluiceway disposed below said opening and adapted to receive and carry away solids removed from said bottom wall by fluid under pressure from said nozzle.
- 10 20 25 In testimony whereof I hereunto affix my signature this 27th day of May, 1929.

JOHN DEUTSCH.
